UNITED STATES PATENT OFFICE

168,202

COMBINED BICYCLE TRAINER WHEEL AND BRACKET

Samuel Wilkens, East Rockaway, N. Y.

Application June 19, 1950, Serial No. 10,627

Term of patent 14 years

(Cl. D34—15)

To all whom it may concern:

Be it known that I, Samuel Wilkens, a citizen of the United States, residing at East Rockaway, in the county of Nassau and State of New York, have invented a new, original, and ornamental Design for a Combined Bicycle Trainer Wheel and Bracket, of which the following is a specification, reference being had to the accompanying drawing, forming a part thereof.

Fig. 1 is a perspective view of a combined bicycle trainer wheel and bracket, showing my new design;

Fig. 2 is a side elevational view thereof;

Fig. 3 is a top plan view thereof;

Fig. 4 is a rear end view of the combined bicycle trainer wheel and bracket in Fig. 3, part being broken away for convenience in illustration; and

Fig. 5 is a side elevational view of the other side of the unit.

I claim:

The ornamental design for a combined bicycle trainer wheel and bracket, substantially as shown.

SAMUEL WILKENS.
